The screenshot shows the Digital Twin Creator app interface. At the top, there are four circular icons: a lock, a question mark, a gear, and a plus sign. Below these are two tabs: 'My Components' (selected) and 'My Projects'. The main area displays a grid of components with their names and small images. A search bar is located at the bottom left. The components listed are: Radiator, One Way Valve, Load Manifold, Circulation Pump, Three Way Valve, and My Experimental Pump. At the bottom, there are sections for 'MY LIBRARIES' and 'MY PROJECTS' with sub-options like 'MY THERMALS', 'MY CONDUCTORS', and 'MY CIRCUITS'.
